UNITED STATES PATENT OFFICE.

CLYDE S. WRIGHT, OF TOLEDO, OHIO, ASSIGNOR TO THE NATIONAL SUPPLY COMPANY, OF TOLEDO, OHIO, A CORPORATION OF OHIO.

SLIP.

1,298,619.

Specification of Letters Patent. Patented Mar. 25, 1919.

Application filed February 14, 1918. Serial No. 217,240.

To all whom it may concern:

Be it known that I, CLYDE S. WRIGHT, a citizen of the United States, residing at Toledo, in the county of Lucas and State of Ohio, have invented new and useful Improvements in Slips, of which the following is a specification.

My invention relates to slips adapted for use in rotary well-drilling machines, drive-pipe rings, spiders, liners, and like devices for gripping and handling pipes, rods, and the like.

It is one of the objects of this invention to provide slips adapted to support pipes, rods, or the like against longitudinal movement between the slips, or to prevent their rotation in the slips, or both. For these purposes, I have provided the slips with inserts of two kinds, one having longitudinal, and 20 the other, transverse teeth, though both kinds may be on the same insert.

Other objects are to reduce the frictional surfaces between the slips and their support, to reduce the weight of the slips by 25 removing large masses of metal at each side of the reduced frictional bearing surfaces, and still make the slips exceedingly strong, to enable comparatively cheap metal to be used for the body of the slips by providing 30 removable toothed inserts made of high grade steel for engagement with the pipe or other article to be handled, to eliminate the necessity of heat-treating the slips, and to reduce and simplify the work of machining 35 the slips. Other objects will appear herein-after.

Referring to the accompanying drawings, Figure 1 is a central vertical section through the table of a rotary well-drilling machine, 40 which shows my improved slips in central vertical section, the pipe gripped thereby being shown in side elevation and the section being taken on the line I—I, Fig. 2; Fig. 2 is an enlarged plan view of the central portion of the apparatus shown on Fig. 1; Fig. 45 3 is an elevation of an insert with longitudinal teeth; Fig. 4 is an elevation of an insert with transverse teeth; Fig. 5 is a bottom plan view of one of the halves of my improved slips; and Fig. 6 is a transverse section of one of the slips.

On the drawings, 1 designates a rotary table for a rotary well-drilling machine. It rotates on the rollers 2 supported by the 55 base 3, having a large central opening 4 into which an extension 5 of the table extends.

The table has a large vertical opening 6 extending entirely through it and provided with internal horizontal shoulders 7. Within this opening is the bushing 8 rotatable 60 with the table and having the external shoulders 9 which rest on the shoulders 7 and fix the vertical position of the bushing in the table. The bushing may in the present case be regarded as a part of the table 65 and both together may be regarded as a holder for the slips.

The bushing is provided with a central vertical opening 10 circular in cross-section and having its defining wall tapering 70 downwardly.

The table is rotated by the bevel pinion 11 which meshes with the teeth 12 on the lower side of the table near its edge.

The apparatus thus far described is well-known.

The bushing 8 is provided with a suitable number of vertical and preferably radial slots 13 extending outwardly from the inner wall of the bushing.

Within the tapering bushing 10 I place a suitable number, preferably two, of slips 14, having their exterior surfaces tapered to correspond with the taper of the wall of the said opening. In order to reduce the weight 85 of the slips and reduce the friction and prevent sticking between the bushing and the slips, I have reduced the tapered surfaces of the slips which contact with the wall of the opening 10, to the ribs or bearing surfaces 90 15, and, except at the top and bottom of the slips, I have these surfaces connected to the bodies of the slips by the webs 16. The bottoms of the slips have the horizontal flanges 17 connected to the sides of the ribs 95 15, a short distance back of the outer faces of the ribs. The lugs 18 extend outwardly into the slots 13 to prevent the slips from turning in the bushing or to cause the slips to rotate with the bushing.

The inner walls of the slips are provided with downwardly extending dovetail slots 21 open above but terminated below by the shoulders 22. Into these slots are slid the inserts or gripping bars 24 and 26 projecting 105 inwardly beyond the vertical walls of the slips, the horizontal sections of the inner walls of the slips preferably coinciding with the arc of a circle slightly larger than the circumference of the pipe to be gripped. 110 Some of the inserts, as 24, have longitudinal serrations, or teeth, 25, and others, as 26,

have transverse serrations, or teeth, 27. In Fig. 2, I have shown one slip provided with inserts having the teeth 25 and the other with inserts having the teeth 27, but the inserts may be variously arranged, so that both kinds may be in each slip or in both slips, according to the class of work to be done or to the particular notions of the user. Rivets or screws 28 may be employed 10 to hold the inserts in place.

29 represents a pipe in the opening between the slips. The teeth 27 prevent the pipe from slipping downwardly while the teeth 25 prevent the pipe from rotating in 15 the slips, in case tools tending to turn the pipe are applied to the same, or to cause the pipe to rotate with the table in case the latter is rotated by the pinion 11. The ribs 15 are located at some distance from the opposing faces of the slips; that is, when the slips are assembled as shown on Fig. 2, the 20 ends of the slips adjacent to their opposing faces are recessed or cut away so that the slips may not, at the points opposite the 25 ends of the said faces, engage the wall of the tapered opening 10 and wedge therein. If the slips were not cut away as just described, and a pipe smaller than that shown on Fig. 2 were used, the slips would move toward 30 each other and lie lower in the opening 10. The distance between the outer edges of the slips on the line I—I would be appreciably 35 lessened while the distance between their outer edges on a line between the slips would remain substantially unchanged, the result being that the slips would be lightly, if at all, gripped by the wall of the opening 10 at points between their vertical edges, while they would be gripped with exceedingly 40 great force at their ends adjacent to their opposing faces, with the result that they would become so wedged in the opening 10 that they could not be removed without exerting 45 great force or breaking the slips. The lugs 18 by their engagement with the side walls of the slots 13 prevent relative rotation of the slips and the table or bushing.

I do not limit my invention to the purposes described since it is evident that it may be employed for various functions 50 where pipes, rods, and the like are to be suspended, raised, lowered, rotated, or held from rotation, or where various combinations of these functions are required, as in drive-pipe rings, spiders, liners, and other 55 devices making use of tapered slips.

The slips herein described are economical in construction since a lower priced material can be used for a greater part of their weight than is possible where the gripping teeth 60 are placed directly on the slips; since a greatly reduced weight of material for the slips may be used; since the machining of the parts is very much reduced and simplified; and since heat treatment of the slips 65 which are large bodies of steel with unequal sectional areas, may be eliminated or largely so. It is necessary to renew the inserts only when worn out, and they may be repeatedly sharpened when dull. Where the teeth are 70 directly on the slips, they can be sharpened, if at all only with the greatest difficulty, and when worn out the whole slip must be scrapped. The described slips, by use of the webbed bearing ribs 15, and the elimination 75 of much metal at each side of these ribs, are made comparatively light, and exceedingly strong for their weight.

I claim—

In a well drilling machine or the like, a 80 holder having a tapering opening circular in cross section, and a plurality of circularly arranged slips having their outer surfaces seated in the said opening and tapered to form bearing surfaces to correspond to the 85 taper of the opening, said slips being cut away at points adjacent to the ends of their opposed faces to prevent the contact of the slips with the wall of the opening at points adjacent to the opposed faces of the slips. 90

Signed at Toledo, Ohio, this 11th day of February, A. D. 1918.

CLYDE S. WRIGHT.
